ATTORNEYS

UNITED STATES PATENT OFFICE.

JAMES HOMER DWIGHT, OF ATLANTA, GEORGIA.

LADDER.

Application filed June 3, 1921. Serial No. 474,624.

To all whom it may concern:

Be it known that I, JAMES H. DWIGHT, a citizen of the United States, and a resident of Atlanta, in the county of Fulton and State 5 of Georgia, have invented certain new and useful Improvements in Ladders, of which the following is a specification.

This invention relates to ladders and more particularly to the rungs of the same.

10 An important object of this invention is to provide a ladder rung which may be readily and conveniently applied to the sides of a ladder in such a manner that the loosening or loss of the rung is absolutely prevented.

A further object of the invention is to provide a ladder rung which is efficient, durable in use and cheap to manufacture.

20 In the accompanying drawing forming a part of this application and in which like numerals are employed to designate like parts throughout the same,

Figure 1 is a perspective of the improved rung.

25 Figure 2 is a side elevation of the same. Figure 3 is a vertical sectional view through the improved rung.

30 Figure 4 is a fragmentary perspective view of the rung, the view illustrating the claws which bite into the sides of the ladder.

Figure 5 is a perspective of a combined bracing and hinge member embodied in the invention.

35 Figure 6 is a side elevation illustrating the rung in its applied position, the view illustrating the stiles of the ladder in dotted lines.

40 Figure 7 is a detail sectional view illustrating the means for slidably and pivotally connecting a pair of arms embodied in the invention.

45 Figure 8 is a side elevation illustrating the ladder rung in the position it occupies preparatory to locking or securing the same to the stiles of the ladder.

50 In the drawing the numeral 5 designates the body of the rung, which body is formed at its ends with L-shaped attaching portions 6 adapted to flatly contact with two sides of the side bars of the ladder. The body 5 is formed with a longitudinal corrugation 7 terminating in branches 8 in the attaching portions 6 and the said branches terminate in inwardly directed teeth 9

formed at the ends of the attaching portions 6. The teeth 9 are forced into the stiles of the ladder so as to firmly attach the rung.

The body 5 which is of elongated formation is formed inwardly of the L-shaped attaching portions 6 with laterally projecting brackets 10 terminating in downwardly directed apertured ears 11 to which a pair of arms 12 are slidably connected. The end portions of the arms 12 are curved longitudinally and pointed to define claws 14 adapted to be forced into the inner faces of the side bars of the ladder by forcing the inner ends of the arms 12 downwardly. The numerals 15 designate longitudinal slots formed in the claws 14, which slots receive 70 pivot pins 16 carried by the downwardly directed ears 11. When the inner ends of the arms 12 are forced downwardly by means to be later described the claws 14 are moved outwardly so that the pins are positioned 75 in the rear or inner portions of the slots thereby limiting the downward movement of the arms 12.

As illustrated in Figure 2 the inner portions of the arms 12 are formed with apertured ears 20 which receive a pivot element 21 whereby the inner portions of the arms are pivotally connected.

55 Tread plates 22 are mounted upon the arms 12 and are formed with downwardly directed attaching flanges 24 securely connected to the sides of the arms by means of rivets 25 or other suitable fastening devices. The tread plates 22 are also formed along their forward longitudinal edges with stop flanges 27 which extend over and engage the upper edge portion of the body 5 so as to limit the downward movement of the arms 12 and thereby relieve the pivot element 21 of the weight of a person standing on the 90 rung. As illustrated particularly in Figure 1 the laterally projecting brackets 10 are extended upwardly or at an angle to the body 5 so that the tread plates 22 will be arranged horizontally when the ladder is 100 supported in an inclined position. That is to say the tread plates 22 will not be inclined transversely when the ladder is supported against the side of a wall or the like.

In order to properly guide the tread plates 105 22 to the position illustrated in Figure 2 the stop flanges 27 are gradually and uniformly decreased in thickness toward their free

edges and will therefore readily seat on the upper edge of the body 5 in the manner illustrated in Figure 3.

Additional bracing means in the nature 5 of a U-shaped hinge member 30 may be employed for limiting the downward movement of the tread plates and preventing the collapse of the round. The U-shaped member 30 has side arms terminating in laterally 10 projecting attaching lugs 31 pivotally connected to the inner portions of the arms 12 by means of pivot elements 33.

The hinge and bracing member 30 is as 15 illustrated in Figure 5 of U-shaped formation and serves as a means to limit the downward movement of the adjacent portions of the arms 12. The U-shaped member 30 is permanently pivoted at its ends to the arms 12 as indicated at 33. I have found in the 20 use of the improved round that the member 30 serves as a convenient means for limiting the downward movement of the adjacent portions of the arms 12.

In applying the improved rung the attaching portions 6 are arranged on opposite sides of the stiles and the tread plates 22 are forced downwardly so as to direct the claws 14 and auxiliary claws 34 carried by the arms 12 into biting engagement with 25 the inner faces of the stiles. This may be readily accomplished by standing on the inner portions of the tread plates and forcing the same downwardly. When thus positioned the rung is absolutely prevented from 30 displacement and in fact weight on the rung will more tightly secure the rung in position since the several claws or teeth will be more tightly engaged with the ladder.

Having thus fully described my invention 40 what I claim is:—

1. A ladder rung comprising a body adapted for arrangement between the stiles of a ladder and having means to engage the stiles, and pivotally connected tread members having their ends formed with means to engage the stiles, said body being engaged by said tread members and limiting the downward pivotal movement of the same.

50 2. A ladder rung comprising a body having means to engage the outer sides of the stiles of a ladder, arms movably associated with said body and having claws adapted to bite into the inner sides of the stiles of the ladder, and tread plates carried by said arms and adapted to engage the body whereby to limit the downward movement of the arms.

3. A ladder rung comprising a rigid body having its ends formed with attaching members and provided adjacent said attaching members with brackets, arms pivotally and slidably connected to said brackets and terminating in claws, and tread plates carried by said arms.

4. A ladder rung comprising a body formed with attaching members and brackets, arms pivotally and slidably connected to said brackets and terminating in claws, and tread plates carried by said arms, 70 said tread plates being formed with downwardly directed stop flanges engaging said body.

5. A ladder rung comprising a body formed with attaching members and provided adjacent said attaching members with brackets, arms pivotally and slidably connected to said brackets and terminating in claws, tread plates carried by said arms, and a combined bracing and hinge member 80 connected to the inner portions of said arms and engaged by said tread plates.

6. A ladder rung comprising arms having claws adapted to bite into the stiles of a ladder and formed with slots, a body having brackets provided with pivot elements passed through said slots, tread plates plates rigidly connected to said arms and having downwardly directed stop flanges gradually reduced in thickness toward their 90 free edges and engaging said body, and a combined bracing and hinge member of U-shaped formation pivoted to said arms and engaged by said tread plates.

7. A ladder rung comprising a pair of 95 pivotally connected arms adapted to be arranged between the stiles of a ladder and having their terminal portions formed with claws adapted for engaging the inner sides of the stiles, and means associated with the 100 arms for embracing the outer sides of the stiles and limiting the downward pivotal movement of the arms.

8. A ladder rung comprising a pair of arms having their adjacent portions pivotally connected, said arms being adapted for arrangement between the stiles of a ladder and having their terminal portions formed with claws adapted for engaging the inner sides of the stiles of a ladder, and a body 110 having connection with said arms and provided with means embracing the outer sides of the ladder, said body forming a means for limiting the downward pivotal movement of the arms.

9. A ladder rung comprising a pair of arms having their adjacent portions pivotally connected and their terminal portions formed with claws adapted for engaging the inner sides of the stiles of a ladder, a 120 body having connection with said arms and provided with means embracing the stiles of the ladder, and tread plates connected to said arms and engaging said body, whereby the downward movement of the arms is 125 limited.

10. A ladder rung comprising a pair of arms having their adjacent portions pivotally connected and their terminal portions formed with curved prongs adapted to bite 130

- into the inner sides of the stiles of a ladder, means associated with the adjacent portions of the arms to prevent the adjacent portions of the arms from moving downwardly beyond a predetermined degree, and a body to which said arms are slidably and pivotally connected.
11. A ladder rung comprising a body having teeth to engage the stiles of the ladder, arms movably associated with said body and having claws adapted to bite into the stiles of the ladder, tread plates carried by said arms and adapted to engage the body whereby to limit the downward movement of the arms, and a combined hinge and bracing member connected to the adjacent portions of the arms.
12. A ladder rung comprising a body adapted for arrangement between the stiles of a ladder and having means to engage the stiles, pivotally connected tread members
- having their ends formed with means to engage the stiles, and a combined bracing and hinge member connected to the adjacent portions of said tread members, said body being engaged by said tread members and limiting the downward pivotal movement of the same.
13. A ladder rung comprising a body adapted for arrangement between the stiles of a ladder and having means to engage the stiles, pivotally connected tread members having their ends formed with means to engage the stiles, said body being engaged by said tread members and limiting the downward pivotal movement of the same, and a combined hinge and bracing member arranged at the adjacent portions of said tread members, said tread members having sliding connection with said body.

JAMES HOMER DWIGHT.
